UNITED STATES PATENT OFFICE

2,599,666

GUMMING AND PASTING MACHINE

Charles A. Surridge, Herne Hill, London, England,
assignor to The Sulby Engineering Development Company Limited, London, England

Application August 31, 1949, Serial No. 113,258
In Great Britain September 3, 1948

10 Claims. (Cl. 11—1)

1

The machine forming the subject of the present invention has been designed to gum or paste together along one edge, sheets of paper or similar substances and is particularly suitable for use in the bookbinding trade as an end papering or plating machine, the gumming or pasting of each book section and end paper or plate and the pressing together of the gummed or pasted parts being performed automatically.

A gumming and pasting machine according to the present invention comprises a gumming wheel, a reservoir or tank for the adhesive and for the delivery of adhesive to the opposite faces of the wheel adjacent its periphery, guiding means for the papers or the like into and out of contact with the gummed surfaces of said wheel so that the opposite edges of the papers are coated with adhesive, means for feeding said papers automatically through the machine past the wheel, positioning means for ensuring correct relative position of said papers during the gumming operation and means for pressing the adhesive coated edges of the papers together.

In order that the invention may be clearly understood and readily carried into effect the invention is hereinafter described with reference to the accompanying drawings wherein:

Figure 1 is a perspective view of a gumming or pasting machine according to the present invention;

Figure 2 is a plan view with the cover removed;

Figure 3 is a transverse section on the line 3—3 in Figure 2 drawn to an enlarged scale;

Figure 4 is a side elevation;

Figure 5 is a transverse section on the line 5—5 in Figure 2 drawn to an enlarged scale;

Figure 6 is a section on the line 6—6 in Figure 2 also drawn to an enlarged scale;

Figure 7 is an inverted plan view of the machine drawn to an enlarged scale;

Figure 8 is a front elevation also drawn to an enlarged scale;

Figures 9 and 10 are respectively views of the gumming wheel and gum reservoir;

Figures 11 and 12 are detail views illustrating more clearly the machine's operation.

The invention will be hereinafter described as applied to a machine primarily intended for end papering or plating book sections, the machine comprising a base 1 supported on legs 2 and fitted with a removable cover or cowling 3. The general arrangement of the machine is clearly illustrated in Figure 1 and in use the operator stands at the right hand end of the machine and picks up from feed trays 4 and 5 a book section and end

2

paper or plate and places them side by side in the machine. Trays 4 and 5 carry each a pile of book sections and end papers or plates, the question as to whether the left hand or right hand tray contains book sections being determined by whether the end papers are to be applied to the front or back of the book. Two such book sections and end papers are indicated by reference numerals 6 and 7 in the process of being placed side by side in the machine.

It will be appreciated that the machine is entirely automatic in operation and includes not only means for feeding a book section and end paper or plate through a machine and delivering these two components firmly secured together on to an output tray 8, but also includes means for correctly positioning the end paper or plate with respect to the book section prior to these two components being gummed along one edge and pressed firmly together when in a gummed condition.

To facilitate the introduction of a book section and end paper or plate hereinafter referred to as an end paper for convenience of description, the machine includes deflector plates 9 arranged on opposite sides of an inlet opening 10 and a central fixed partition 11. The arrangement is such that the opening 10 in conjunction with the deflector plates 9 form a feed hopper or virtually two feed hoppers on opposite sides of the central fixed partition 11, the one part of the hopper, for example, on the left hand side being used to receive a book section and that on the right an end paper, the partition 11 serving to maintain the components in spaced relationship. To facilitate the introduction of the book section and end paper the cover 3 of the machine is recessed as at 12 on opposite sides of the partition.

As it is necessary to accurately position the end papers with respect to the book sections, i. e., to ensure that the two components are aligned head to head, the machine includes an endless belt type of feed 13, see particularly Figures 2, 11 and 12, the feed 13 being in the form of a unidirectionally driven endless belt passing around pulleys 14 arranged at opposite ends and driven by suitable means hereinafter described. The endless belt is fitted with a laterally projecting pin 15 which as a result of linear movement of the belt is adapted to come into engagement with the head of the book section and end paper and feed these two components forwardly into the machine. The operation of this feeding device is clearly shown in Figure 11

which defines a book section and end paper placed side by side in the hopper, but separated by means of partition 11. In Figure 11 the pin 15 is in process of moving along into the position shown in Figure 12 in which it has made contact with the head of the book section and end paper to move both components forwardly into the machine. The lower edges of the book section and end paper engage longitudinally arranged guides 16 which guides include a central shallow division 16a extending to the periphery of the gumming wheel for the purpose of ensuring passage of book section and end paper one on either side of the gumming wheel. The endless feed belt may be adjusted from time to time by means of a tensioning screw 17 shown in Figure 2.

The accurately positioned book section and end paper is fed forwardly in spaced relationship and in alignment between the two halves of an endless belt conveyor, the belts being indicated by reference numeral 18 and passing around pulleys 19, the two conveyor belts being driven at a uniform speed, but in opposite directions to pass the book section and end paper towards the output end of the machine. On the book section and end paper coming into contact with the two belts of the conveyor they are brought together and finally passed on opposite sides of a gummed wheel hereinafter to be described. Suitable means are provided for tensioning the two conveyor belts such, as for example, tension rollers 20 which engage the outside walls of the two belts. Two of these pulleys 19 have gear wheels 21 associated therewith which gear wheels are in meshing engagement to ensure uniform movement of the belts and prevent any possibility of the book section and end paper being creased during its passage through the conveyor.

A fixed conveyor plate 22 is arranged inside the one belt over which plate that belt runs, whilst a second conveyor plate 23 is associated with the other conveyor belt and is urged into contact therewith by means of springs 24 so that the belts resiliently grip the book section and end paper and not only maintain alignment of these components prior to them coming into contact with the gumming wheel, but also press the components together when in a gummed condition to ensure the components being firmly stuck together. In addition finger springs 62 are preferably provided which engage the back section or end paper direct over that part of the section or end paper which has been gummed for the purpose of additionally ensuring a good stick.

After passing the gumming wheel the book section and end paper continues through the machine and finally engages a delivery guide 25 which is clearly illustrated in Figures 1 and 2, the delivery guide being in the form of a vertically arranged plate carrying a delivery runner 26 which is adjustably mounted in a slot 27 and serves to deflect the book section and its associated end paper into the output delivery tray 8.

Referring now particularly to Figures 5, 9 and 10 which illustrate in detail the construction of the gumming wheel and its associated reservoir or tank for containing the adhesive, the gumming wheel 28 takes the form of a comparatively thin disc-like component which is tapered towards its periphery and is detachably mounted upon a supporting shaft 29 running in bearings in a journal 30 which in turn has a pin and slot connection 31 with a cover plate 32 for a bath 33 which is supplied with adhesive from an adhesive containing reservoir or tank 34. The tank is

fitted at its upper end with a removable plug 35 for filling purposes and has an outlet opening 36 at its lower end in connection with a pipe 37 leading to the bath 33, the opening 36 being closable by means of an axially slidable valve 38 which can be slid in and out of the position shown in Figure 5 so that the opening 36 is either covered or uncovered, the supply of adhesive from the reservoir to the bath 33 being thereby controlled. Shaft 29 is fitted with a pulley 40 which is driven through the medium of a belt drive.

The driving mechanism for the gumming wheel, endless belt feed and endless belt conveyor is shown clearly in Figure 7, the various belts being situated below the under surface of the base 1, Figure 7 representing an inverted plan view of the machine. The drive includes an electric motor 41, the output shaft of which carries a pulley over which passes a belt 42 which in turn passes around pulley 43 on which is associated a similar pulley 44 which in turn carries a second belt 45 passing around pulley 46 on which is associated a similar pulley 47 driving a belt 48 which in turn passes around a pulley 49 associated with one of the conveyor pulleys 19. The driving shaft 50 of pulleys 46 and 47 has a driving connection with one of pulleys 14 associated with the endless belt feed. Pulley 43 has a further pulley associated with it of smaller size over which passes a belt 51 which in turn passes over a jockey pulley 52 on which is associated a further jockey pulley 53 over which runs a further belt 54 which finally passes around pulley 40 associated with the gumming wheel. In this way the whole of the moving parts of the machine are operated by means of a single driving motor.

A scraper 55 is associated with the gumming wheel 28 for the purpose of removing excess adhesive from the periphery of the wheel, the scraper serving to meter the quantity of gum which is carried up by the wheel from the bath 33. Lateral adjustment of the wheel to ensure correct entry of the periphery of the wheel between a book section and end paper is effected by adjustment of the screws 56. Vertical adjustment of the gumming wheel and the reservoir and the tank is effected by means of a knurled adjusting knob 57 which is associated with the screw threaded extremity of a downwardly depending pin 58 secured to the base 1, the reservoir being slidable on this pin and a diametrically opposite pin 59.

To provide an additional adjustment between the two conveyor elements, an adjusting device such as is shown in Figure 5 may be provided, this adjusting device taking the form of a knurled adjusting knob 60 which when operated varies the resilient pressure of a coiled spring 61 acting on the conveyor plate 23 near the input end of the conveyor.

It will be appreciated from the foregoing description of the invention that the book section and end paper on reaching the input end of the conveyor 18 will pass on opposite sides to the periphery of the gumming wheel 28 and the gumming wheel will thus apply adhesive to the opposite edges of the book section and end paper in the manner shown in Figure 5. The width over which adhesive is applied is adjustable by varying the effective height of the gumming wheel and after passing the gumming wheel, the two parts of the conveyor 18 will firmly press the book section and end paper together along the

gummed edges to ensure the components being firmly stuck together.

To facilitate entry of the lower edges of the book section and end paper into the longitudinally arranged guides 16, the fixed partition 11 is of tapering form in cross section.

The reservoir or tank for the adhesive operates on the barometric principle, the tank being closed at its upper end when the machine is in use and consequently a uniform depth of adhesive is maintained in the bath 33.

To ensure that the pin 15 does not foul the book section and end paper as these components enter the conveyor, the belts of the conveyor are arranged to move faster linearly than the feed belt carrying the pin 15, the pin being thus left behind as the book section and end paper enters the conveyor.

Furthermore, it will be appreciated that by providing a sealed tank or reservoir for the adhesive, skinning of the gum or paste will be prevented, only that quantity in immediate use in the bath being open to the air. In addition the means provided for controlling the level of the gum or paste in the bath hereinbefore described ensures that the quantity of adhesive carried upward by the gumming wheel is constant in quantity and thus ensures uniformity of the gummed or pasted book sections and end papers or plates.

What I claim is:

1. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of at least one face of said disc during rotation thereof; means located adjacent to another part of the peripheral edge portion of said disc for moving said pair of sheet members in side by side relation to each other with said edge portions confronting each other and in a direction substantially tangential to said disc, said disc projecting between said confronting edge portions of said sheet members so that said edge portions are located on opposite faces of said disc and overlap a part of the peripheral edge portion thereof, whereby at least one of said confronting edge portions of said sheet members will have paste applied thereto by said rotating disc; and means located in the path of said sheet members after the same have passed by said disc for conveying said sheet members away from said disc with said confronting edge portions at least partly pasted together and for simultaneously pressing said sheet members together so that they will be joined at the edge portions thereof by said paste.

2. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of at least one face of said disc during rotation thereof; means located adjacent to another part of the peripheral edge portion of said disc for moving said pair of sheet members in side by side relation to each other with said edge portions confronting each other and in a direction substantially tangential to said disc, said disc projecting between said confronting edge portions of said

sheet members and at least said peripheral edge portion of said one face of said disc contacting one of said edge portions of said sheet members so that said edge portions are located on opposite faces of said disc and overlap a part of the peripheral edge portion thereof, whereby at least one of said confronting edge portions of said sheet members will have paste applied thereto by said rotating disc; and means located in the path of said sheet members after the same have passed by said disc for conveying said sheet members away from said disc with said confronting edge portions at least partly pasted together and for simultaneously pressing said sheet members together so that they will be joined at the edge portions thereof by said paste.

3. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of at least one face of said disc during rotation thereof; a pair of spaced substantially parallel guide ways located adjacent to each other and extending along a line which is substantially tangential to said disc, said guide ways each having an end portion located adjacent to the respective faces of said disc and along a line located within and extending across the outer circumference of said disc; means for moving a pair of sheet members along said guide ways towards said disc in side by side relation to each other with said edge portions of said sheet members located in said guide ways and confronting each other, whereby when said sheet members leave said end portions of said guide ways they move along respective faces of said disc with said edge portions of said sheet members contacting said faces so that at least one of said edge portions has the paste material on said peripheral edge portion of said disc applied thereto; and means located on the side of the disc axis distant from said guide ways for conveying said sheet members away from said disc and for simultaneously pressing said sheet members against each other, whereby said edge portions thereof will be joined to each other by said paste.

4. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of at least one face of said disc during rotation thereof; a pair of spaced substantially parallel guide ways located adjacent to each other and extending along a line which is substantially tangential to said disc, said guide ways each having an end portion located adjacent to the respective faces of said disc and along a line located within and extending across the outer circumference of said disc; means for moving a pair of sheet members along said guide ways towards said disc in side by side relation to each other with said edge portions of said sheet members located in said guide ways and confronting each other, whereby when said sheet members leave said end portions of said guide ways they move along respective faces of said disc with said edge portions of said sheet members contacting said faces so that at least one of said edge portions has the paste material on said peripheral edge portion of said disc

applied thereto, said means for moving said pair of sheet members comprising an elongated element extending transversely across said guide means and mounted for movement along a path overlying said guide ways, whereby said elongated element engages parts of said sheet members located adjacent to said edge portions thereof to move said sheet members along said guide ways and to align said parts of said sheet members with each other so as to thereby also align said edge portions with respect to each other; and means located on the side of the disc axis distant from said guide ways for conveying said sheet members away from said disc and for simultaneously pressing said sheet members against each other, whereby said edge portions thereof will be joined to each other by said paste.

5. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of at least one face of said disc during rotation thereof; a pair of spaced substantially parallel guide ways located adjacent to each other and extending along a line which is substantially tangential to said disc, said guide ways each having an end portion located adjacent to the respective faces of said disc and along a line located within and extending across the outer circumference of said disc; means for moving a pair of sheet members along said guide ways towards said disc in side by side relation to each other with said edge portions of said sheet members located in said guide ways and confronting each other; whereby when said sheet members leave said end portions of said guide ways they move along respective faces of said disc with said edge portions of said sheet members contacting said faces so that at least one of said edge portions has the paste material on said peripheral edge portion of said disc applied thereto, said means for moving said pair of sheet members comprising an elongated element extending transversely across said guide means and connected at one end thereof to an endless belt means located adjacent and substantially parallel to said guide ways so that said elongated element is mounted for movement along a path overlying said guide ways, whereby said elongated element engages parts of said sheet members located adjacent to said edge portions thereof to move said sheet members along said guide ways and to align said parts of said sheet members with each other so as to thereby also align said edge portions with respect to each other, and means for moving said endless belt means; and means located on the side of the disc axis distant from said guide ways for conveying said sheet members away from said disc and for simultaneously pressing said sheet members against each other, whereby said edge portions thereof will be joined to each other by said paste.

6. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of at least one face of said disc during rotation thereof; a pair of spaced substantially parallel guide ways located adjacent to each other and extending along a line which is substantially tangential to

said disc, said guide ways each having an end portion located adjacent to the respective faces of said disc and along a line located within and extending across the outer circumference of said disc; means for moving a pair of sheet members along said guide ways towards said disc in side by side relation to each other with said edge portions of said sheet members located in said guide ways and confronting each other, whereby when said sheet members leave said end portions of said guide ways they move along respective faces of said disc with said edge portions of said sheet members contacting said faces so that at least one of said edge portions has the paste material on said peripheral edge portion of said disc applied thereto; and means located on the side of the disc axis distant from said guide ways for conveying said sheet members away from said disc and for simultaneously pressing said sheet members against each other, whereby said edge portions thereof will be joined to each other by said paste, said means for conveying said sheet members away from said disc and simultaneously pressing said sheet members together comprising a pair of endless belt means arranged with elongated portions thereof confronting each other and located at one end adjacent to said disc so as to receive the sheet members from said disc, resilient means for urging said elongated portions of said pair of endless belt means toward each other so that they press the sheet members therebetween and means for rotating said pair of endless belt means in opposite directions so that both of said elongated portions thereof move in a direction away from said disc.

7. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of at least one face of said disc during rotation thereof; a pair of spaced substantially parallel guide ways located adjacent to each other and extending along a line which is substantially tangential to said disc, said guide ways each having an end portion located adjacent to the respective faces of said disc and along a line located within and extending across the outer circumference of said disc; means for moving a pair of sheet members along said guide ways towards said disc in side by side relation to each other with said edge portions of said sheet members located in said guide ways and confronting each other, whereby when said sheet members leave said end portions of said guide ways they move along respective faces of said disc with said edge portions of said sheet members contacting said faces so that at least one of said edge portions has the paste material on said peripheral edge portion of said disc applied thereto, said means for moving said pair of sheet members comprising an elongated element extending transversely across said guide means and connected at one end thereof to an endless belt means located adjacent and substantially parallel to said guide ways so that said elongated element is mounted for movement along a path overlying said guide ways, whereby said elongated element engages parts of said sheet members located adjacent to said edge portions thereof to move said sheet members along said guide ways and to align said parts of said sheet members with each other so as to thereby also align said edge portions with

respect to each other, and means for moving said endless belt means; and means located on the side of the disc axis distant from said guide ways for conveying said sheet members away from said disc and for simultaneously pressing said sheet members against each other, whereby said edge portions thereof will be joined to each other by said paste, said means for conveying said sheet members away from said disc and for simultaneously pressing said sheet members together comprising a pair of endless belt means arranged with elongated portions thereof confronting each other and located at one end adjacent to said disc so as to receive the sheet members from said disc, resilient means for urging said elongated portions of said pair of endless belt means toward each other so that they press the sheet members therebetween and means for rotating said pair of endless belt means in opposite directions so that both of said elongated portions thereof move in a direction away from said disc.

8. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of said disc during rotation thereof, said means for applying a paste material to said disc comprising a bath of paste material located adjacent to the lowermost part of said disc and overlapping a part of the peripheral edge portion thereof and means for maintaining the level of the paste material in the bath above only the lowermost part of said disc so that said peripheral edge portion of said disc passes through said paste material during the rotation of said disc; a pair of spaced substantially parallel guide ways located adjacent to each other and extending along a line which is substantially tangential to said disc, said guide ways each having an end portion located adjacent to the respective faces of said disc and along a line located within and extending across the outer circumference of said disc; means for moving a pair of sheet members along said guide ways towards said disc in side by side relation to each other with said edge portions of said sheet members located in said guide ways and confronting each other, whereby when said sheet members leave said end portions of said guide ways they move along respective faces of said disc with said edge portions of said sheet members contacting said faces so that at least one of said edge portions has the paste material on said peripheral edge portion of said disc applied thereto; and means located on the side of the disc axis distant from said guide ways for conveying said sheet members away from said disc and for simultaneously pressing said sheet members against each other, whereby said edge portions thereof will be joined to each other by said paste.

9. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of said disc during rotation thereof, said means for applying a paste material to said disc comprising a bath of paste material located adjacent to the lowermost part of said disc and overlapping a part of the periph-

eral edge portion thereof and means for maintaining the level of the paste material in the bath above only the lowermost part of said disc so that said peripheral edge portion of said disc passes through said paste material during the rotation of said disc, said means for maintaining the level of the paste material above the lowermost portion of said disc comprising a reservoir of paste material communicating with said bath and valve means located between said reservoir and bath for admitting the paste material from said reservoir to said bath in order to maintain the desired level of the paste material in said bath; a pair of spaced substantially parallel guide ways located adjacent to each other and extending along a line which is substantially tangential to said disc, said guide ways each having an end portion located adjacent to the respective faces of said disc and along a line located within and extending across the outer circumference of said disc; means for moving a pair of sheet members along said guide ways towards said disc in side by side relation to each other with said edge portions of said sheet members located in said guide ways and confronting each other, whereby when said sheet members leave said end portions of said guide ways they move along respective faces of said disc with said edge portions of said sheet members contacting said faces so that at least one of said edge portions has the paste material on said peripheral edge portion of said disc applied thereto; and means located on the side of the disc axis distant from said guide ways for conveying said sheet members away from said disc and for simultaneously pressing said sheet members against each other, whereby said edge portions thereof will be joined to each other by said paste.

10. Apparatus for pasting together a pair of edge portions of a pair of sheet members, respectively, comprising, in combination, a rotatably mounted disc; means for rotating said disc; means located adjacent to a part of the peripheral edge portion of said disc for applying a paste material to the peripheral edge portion of said disc during rotation thereof, said means for applying a paste material to said disc comprising a bath of paste material located adjacent to the lowermost part of said disc and overlapping a part of the peripheral edge portion thereof and means for maintaining the level of the paste material in the bath above only the lowermost part of said disc so that said peripheral edge portion of said disc passes through said paste material during the rotation of said disc, said means for maintaining the level of the paste material above the lowermost portion of said disc comprising a reservoir of paste material communicating with said bath and valve means located between said reservoir and bath for admitting the paste material from said reservoir to said bath in order to maintain the desired level of the paste material in said bath; a pair of spaced substantially parallel guide ways located adjacent to each other and extending along a line which is substantially tangential to said disc, said guide ways each having an end portion located adjacent to the respective faces of said disc and along a line located within and extending across the outer circumference of said disc; means for moving a pair of sheet members along said guide ways towards said disc in side by side relation to each other with said edge portions of said sheet members located in said guide ways and confronting each other, whereby when said sheet members leave said end portions of said guide ways they

move along respective faces of said disc with said edge portions of said sheet members contacting said faces so that at least one of said edge portions has the paste material on said peripheral edge portion of said disc applied thereto, said means for moving said pair of sheet members comprising an elongated element extending transversely across said guide means and connected at one end thereof to an endless belt means located adjacent and substantially parallel to said guide ways so that said elongated element is mounted for movement along a path overlying said guide ways, whereby said elongated element engages parts of said sheet members located adjacent to said edge portions thereof to move said sheet members along said guide ways and to align said parts of said sheet members with each other so as to thereby also align said edge portions with respect to each other, and means for moving said endless belt means; and means located on the side of the disc axis distant from said guide ways for conveying said sheet members away from said disc and for simultaneously pressing said sheet members together comprising a pair of endless belt means arranged with elongated portions thereof confronting each other and located at one end adjacent to said

5 disc so as to receive the sheet members from said disc, resilient means for urging said elongated portions of said pair of endless belt means toward each other so that they press the sheet members therebetween and means for rotating said pair of endless belt means in opposite directions so that both of said elongated portions thereof move in a direction away from said disc.
